SOUND RECORDING

Ellsworth D. Cook, Scotia, N. Y., assignor to Radio Corporation of America, a corporation of Delaware

Application June 27, 1936, Serial No. 87,618

6 Claims. (Cl. 179—100.3)

This invention relates to a novel method of apparatus for sound recording and more particularly to a novel method and apparatus for producing photo-phonographic sound records with ground noise reduction.

Some of the older type photographic sound records had a large unused clear portion wherein approximately half of the sound track was left clear at no modulation. This resulted in undesired sounds when reproduced due to the unexposed but developed silver grains in the clear area of the film and also due to dust, dirt, scratches, etc. on the film. In order to avoid this noise, which is generally referred to as "ground noise", it was proposed in Robinson Patent 1,854,159 to shift the axis of the sound track so as to blacken all but the used portion of the positive sound track. In McDowell Patent 1,855,197 it was proposed to accomplish this blacking of the positive sound track by interposing a shutter between the recording galvanometer and the film to prevent exposure of the unused portion of the negative film and thereby cause a corresponding blackening of the positive film.

It was proposed in Dimmick Patent 1,999,721 to apply ground noise reduction to a bilaterally modulated sound track and Dimmick preferred to use a multiplex sound track. In the present invention the sound track produced is somewhat similar in appearance to a single section of the Dimmick sound track but differs therefrom in that instead of the outer envelope of the sound track being changed in width in accordance with the volume an axial masking track is provided which functions in a manner similar to the McDowell masking track.

One object of the invention is to produce an anti-ground noise sound track without the use of a rectifier or low pass filter circuit.

Another object of my invention is to provide a sound track which may be printed either with or without ground noise reduction.

Another object of my invention is to provide simplified records for producing anti-ground noise sound track.

Another object of my invention is to provide an optical means for producing a record corresponding to the envelope of the sound waves.

Further objects of my invention will be apparent to those skilled in the art from a reading of the following specification and an inspection of the accompanying drawing in which

Figure 1 is a schematic illustration of a recorder according to my invention.

Figure 2 is an enlarged view of the sound record as recorded.

Figure 3 is an enlarged view of the masking record as recorded, and

Figure 4 is an enlarged view of a positive print 5 corresponding to Figs. 2 and 3.

Referring first to Figure 1, 10 indicates the exciter lamp, the light from which is focused by the lens 11 upon the galvanometer mirror 15 after passing through the aperture plate 12 which is 10 provided with apertures 13A, B and C, the dimensions of which are determined as hereinafter described. Light passing through the aperture 13A passes through the lens 14 onto the mirror 15 of the galvanometer 16 since it is reflected 15 through the lens 14 to the lens 17. The focal length of the lens 14 is so chosen that images 13a, 13b and 13c of the apertures 13A, 13B and 13C are thrown on the slit plate 18 which is provided with a narrow slit 19 and a wider slit 19'. Lens 17 focuses image of filament at mirror 15 on to objective lens 21. The light passing through the slits 19 and 19' is focused on the film 20 by a lens 21. The slit 19 is made of such a width that the image thereof on the film 20 is of the order 25 of ".001'" or less in order that sound waves of sufficiently high frequency may be properly recorded as indicated at 22.

It will be apparent that the light passing through the slit 19 will be imaged on the film 30 as a fine line varying in length according to the position of the triangular spot 13a on the slit as the galvanometer mirror 15 is vibrated around the horizontal axis. The triangular spot will move up and down across the slit 19 in accordance with 35 the sound waves thereby producing a sound record such as that shown in Fig. 2 wherein the upper portion represents sounds of a high amplitude and low frequency while the lower portion represents sounds of a lower amplitude and 40 a higher frequency.

The height of the aperture 19' is so chosen that the image thereof on the film 20 is one wave length of the lowest sound frequency to be recorded. It will be apparent that as the mirror 45 15 is oscillated by the galvanometer 16 the images 13b and 13c will be moved vertically across this slit 19' and will produce a record such as shown in Fig. 3 which is complementary to the record shown in Fig. 2. This record as distinguished from the record of Fig. 2 does not correspond with the individual sound waves but corresponds only with the envelope of the sound waves due to the width of the slit 19'. The amplifier, of course, either will be so constructed as 50 55

to pass no frequencies below the frequency corresponding to the width of the slit 19' or will be provided with a filter circuit cutting off the lower frequencies.

5 The comparison of Figs. 2 and 3 will show that the interior envelope of the record of Fig. 2 corresponds with the transparent portion of the record of Fig. 3. When the record of Fig. 2 is printed onto a positive film it will produce blackened sound records at the outer margins of the sound track as indicated at 21 and 22 in Fig. 4 leaving the portion corresponding to the blackened portion in Fig. 2 clear. If the record of Fig. 3 is then printed on this positive sound track 10 it will produce a blackened center portion 23 corresponding to the internal envelope of the sound record and thus prevent the transmission of light by the unused portions of the film. It 15 will be apparent to those skilled in the art that it is not necessary for me to run the positive film through the printer twice in order to produce the record of Fig. 4 but that I can superpose the images 21, 22 and 23 optically and thereby produce the record of Fig. 4 at a single printing operation. It will further be apparent that instead of 20 producing these two records laterally adjacent on a single film I may produce them in the same lateral position on two separate films thereby permitting me to perform the printing operation 25 without any lateral adjustment of the film in the printer.

It may be desirable, in some instances, as, for example, if the film is of low sensitivity, to use a higher exposure on the masking track than on 30 the sound wave track. This might be accomplished, for example, by using a light absorbing glass or a partially exposed photographic emulsion and correspondingly increasing the light 35 intensity.

40 If it were desired to print a negative instead of a positive sound track from the combined printing of the negatives of Fig. 2 and Fig. 3 the aperture for the masking track would be made to increase with the space between the 45 apertures 13B and 13C, in which case the masking track would correspond with the exterior envelope of the sound track of Fig. 2 and the composite print would be a corresponding negative from which positive sound records could be 50 subsequently printed.

Having now described my invention, I claim:

1. Sound recording apparatus including means for producing a substantially triangular beam of light, means for producing two beams of 55 light complementary to the sides of said triangle,

means for vibrating all of said beams in accordance with sound waves, means for selecting a narrow portion of said triangular beam and for selecting portions of said complementary beams corresponding in width with the wave length of the lowest frequency to be recorded and means for directing said selected portions onto a photographic record surface.

2. Apparatus for producing a record of the envelope of sound waves comprising means for directing upon a record surface a beam of light having a width in the direction of motion of the said surface corresponding to one wave length of the lowest sound frequency of which the envelope is to be recorded, and means for vibrating said beam of light transversely of the record surface in accordance with the sound vibrations.

3. The method of making a record of the envelope of sound vibrations comprising the steps of directing onto a record surface a beam of light having one dimension corresponding to one wave length of the lowest sound vibrations whose envelope is to be recorded, vibrating said beam in a direction perpendicular to said first direction in accordance with the sound waves, and moving the record surface along the said first direction at an appropriate speed.

4. Electrical impulse recording apparatus including means providing a light slit having relatively wide and narrow portions, means for directing a light beam on the relatively narrow portion of said slit, means for directing on said relatively wide portion a light beam which is complementary to a side of said first mentioned beam, and means for vibrating said beam in accordance with said impulses.

5. Electrical impulse recording apparatus including means providing a light slit having relatively wide and narrow portions, means for directing a triangular light beam on said relatively narrow portion, means for directing on said relatively wide portion a pair of light beams complementary to the sides of said triangular beams, and means for vibrating said beams in accordance with said impulses.

6. Electrical impulse recording apparatus including means providing a light slit having alined relatively wide and narrow portions, means for directing a light beam on the relatively narrow portion of said slit, means for directing on said relatively wide portion a light beam which is complementary to a side of said first mentioned beam, and means for vibrating said beams in accordance with said impulses.

ELLSWORTH D. COOK. 55
